[57] **CLAIM**

The ornamental design of a neck and ear warmer, as shown and described.

DESCRIPTION

FIG. 1 is a top plan view showing our new design;

FIG. 2 is a rear elevation view thereof;

FIG. 3 is a right side elevation view thereof;

FIG. 4 is a front elevation view thereof;

FIG. 5 is a bottom plan view thereof;

FIG. 6 is a left side elevation view thereof; and,

FIG. 7 is front, right side perspective view of the design as worn.

The dashed lines in FIGS. 2 and 4 represent conventional stitching. The broken line showing of the human form in FIG. 7 is for illustrative purposes only and forms no part of the claimed design.
